MANUAL TURN AUTO SIGNAL

Anatol N. Andrews, Los Angeles, Calif.

Application June 21, 1935, Serial No. 27,759

2 Claims. (Cl. 177—329)

My invention is a safety device for night driving which indicates right and left turns and stops.

Fig. 1 is a cross section of the device and a dry battery.

Fig. 2 is a cross section of the upper portion of the device and a storage battery.

Fig. 3 shows the device with its medium of attachment maintaining its standard shape.

Fig. 4 shows the device with its medium of attachment adjusted by bending to fit an individual automobile door.

Fig. 5 shows an automobile door and the device adjusted laterally along the door glass.

Fig. 6 is a cross section of an automobile door and window and indicates how the device is adjusted to the door and shows its dependent positions over the edge of the window.

Fig. 7 is a cross section of the auto door and window and shows the position of the device over the edge of the window when it is raised.

Fig. 8 is a cross section of the auto door and window and shows the device resting against the inside door casing when the window is closed.

The device consists of a small electric bulb 1, Figure 1, which screws into a metal tube 5, and rests against an electric contact 2, supported by a fibre disc 3. The contact 2, is connected to a wire 4, which extends through the tube 5, and terminates at contact 7, supported by a fibre disc 6. The metal tube 9, is an enlarged portion of tube 5 and serves as a handle for raising or lowering the light 1, and also serves as a case in which is contained a dry battery 8, which contacts with the contact 7. A push button 12, is supported by the fibre disc 10 and is held in position by the spring 11. Pressing in the push button 12, causes the electric bulb 1, to become lighted.

The leather strap 15, is connected to the tube 9, by means of rivets 14. The other end of the leather strap 15, is connected to a metal bar 13, by means of rivets 14.

The device is entirely hand operated. As indicated by Figure 6, the operator grasps the tube 9, in his hand and raises the light 1, to any desired position as indicated. Figure 6, shows how the device is attached to the automobile door. The metal bar 13, fits in between the inner door casing 28, and the window 29. The leather strap 15, extends over the top of the window and comes to rest against the outer door casing, forming a soft pad which prevents the tube 9, from chafing the outer door casing 27.

The leather strap 15, is of sufficient length so that the metal bar 13, and the metal tube 5 remain at a minimum angle as indicated in Figure 3, thus preventing the light 1, from coming into contact with the door of the automobile and becoming damaged. The leather strap 15, can be adjusted to fit any automobile by simply bending the upper portion of the metal bar 13, as indicated in Figure 4. The metal bar 13, is of sufficient weight to overbalance the weight of the other parts of the device thus preventing the light 1, from coming into contact with the door as indicated in Figure 6.

The device can be adjusted laterally to suit the arm length of any driver by simply sliding the entire device forward or backward as illustrated in Figure 5.

The device can be operated with the window completely open or partially closed as the leather strap 15, is supported by the top of the window 29, and the entire device slides up or down with the window 29, as illustrated in Figure 7.

When the window is entirely closed the tube 5, is carried inside the automobile, coming to rest against the inside door casing as illustrated in Figure 8.

Figure 2, shows the same device converted, so that the light 1, can be lighted from the automobile storage battery 18, in place of the dry cell battery 8. The construction of the storage battery type differs in the following respects:

The dry cell battery 8, is eliminated from the case 17, Figure 2. The wire 16 extends through the fibre disc 21, and terminates in the electric contact 22. The push button 26, is supported by the fibre disc 23, and held in place by the spring 24. The fibre core 25, insulates the push button 26, from the metal case 17. The wire 19, connects the battery 18, to the metal case 17. The wire 20, connects the battery 18, to the push button 26. Pressing the push button in causes the electric bulb to become lighted.

I claim:

1. A manually operated direction signal comprising a signal member consisting of a relatively long tubular housing having a battery and a manually operated switch mounted in one end thereof which end is the upper end of the housing when the signal member is attached to an automobile, an electric lamp mounted at the lower end of the housing, the lamp, battery and switch being connected in a series circuit relationship, a bar of relatively thin metal adapted to loosely fit between the door glass and inside edge of the automobile door, said metal bar having

ing a greater mass than that of the signal member, and a flexible member connecting the upper end of the metal bar with the upper end of the signal member, said flexible member being 5 of a length to allow the signal member to assume a dependent position over the edge of the automobile door.

2. A manually operated direction signal comprising a signal member consisting of a relatively long tubular housing having an electric lamp mounted at the lower end thereof and a manually operated switch mounted adjacent to 10 the upper end, which end is the upper end of the housing when the signal member is attached

to an automobile, the lamp and switch being connected with a battery in series circuit relationship, a bar of relatively thin metal adapted to loosely fit between the door glass and inside edge of the automobile door, said metal bar having a greater mass than that of the signal member, and a flexible member connecting the upper end of the metal bar with the switch end of the signal member, said flexible member being of a length to allow the signal member to assume a dependent position over the edge of the automobile door. 5

ANATOL N. ANDREWS.
